THE NORRIS PETERS CO., WASHINGTON, D. C.

UNITED STATES PATENT OFFICE.

JOHN J. BUCKLEY, OF BOSTON, MASSACHUSETTS.

FLY-PAPER HOLDER.

1,103,259.

Specification of Letters Patent.

Patented July 14, 1914.

Application filed April 23, 1913. Serial No. 763,131.

To all whom it may concern:

Be it known that I, JOHN J. BUCKLEY, a citizen of the United States, residing at Boston, in the county of Suffolk and State of Massachusetts, have invented certain new and useful Improvements in Fly-Paper Holders; and I do hereby declare the following to be a full, clear, and exact description of the invention, such as will enable others skilled in the art to which it appertains to make and use the same.

This invention relates to improvements in holders for fly paper, or other devices carrying surfaces adapted to catch insects, and germs, and an object of the invention is to provide a holder which will keep the sticky surfaces of the paper out of contact with other objects.

A further object of the invention is to provide a holder with a folding frame such that the same may be hung from a chandelier or from a wall and still present a surface for the purpose of catching insects.

A still further object of the invention is to provide a folding fly paper holder having adjusting cords for holding the frame in any predetermined position.

A still further object of the invention is to provide the fly paper holder with turned up sides and troughs at its ends, these turned-up ends or troughs being adapted to receive curved ends of fly paper so that when the ends are hung in an inclined plane, the adhesive carried by the paper will not run off of the paper on to the holder.

With these and other objects in view, the invention consists in certain constructions, combinations and arrangements of the parts that shall hereinafter be fully described, and then specifically pointed out in the claims.

In the drawings, Figure 1 is a perspective view of the holder in flat position, the same being ready for reception of fly paper or the like; Fig. 2 is a perspective view of the holder folded so as to rest upon one side, there being shown adjusting cords and cleats for holding the same; Fig. 3 shows the invention as applied to a wall; Fig. 4 shows the invention as suspended over a chandelier or other fixture in a room; Fig. 5 is a side elevation of the holder showing the same suspended from a wall, the planes of the adhesive paper being perpendicular to the wall; and Fig. 6 is a perspective view of the holder in folded position.

Like reference characters designate cor-

responding parts throughout the several views.

The general embodiment of this invention aims to provide two or more hinged sections each of which has the sides thereof upturned to form flanges, while the outside ends of the extreme sections are provided with troughs or scuppers which are adapted to receive curved ends of adhesive paper, and also serve to hold the ends of the paper in place. For the purpose of adjusting the hinged sections, there is provided a plurality of cords engaging appropriately placed cleats, these cords being removable and wound around the cleats to hold the suspended parts of the holder.

Referring to the drawings, the holder is shown as formed of two parts 1 and 2 respectively, these parts being hinged together as indicated in Fig. 2, by having a rod passing through portions of the abutting ends of adjacent sections, this method of hinging being simply one of several schemes which may be used. The section 1 has its opposite sides thereof turned up to form flanges 5—5 these flanges being formed with a recess in the central portion thereof in order to improve the appearance of the holder. Extending between the ends of the flanges, and preferably formed of the same material, with the section, is a trough or receptacle 4, this trough having three sides closed, and having its ends formed by the outer extremities of the flanges 5. The section 2 has its ends 3—3 upturned, but the upturned sides or flanges 5—5 are slightly farther apart than the flanges 3—3 so that as the paper folds, the flanges 3—3 will be contained within the flanges 5—5. There is provided on the outer end of the section 2, a trough 6 formed similar to the trough 4. Extending from the back of each of the sections 1 and 2, is a hanger 7, this hanger being provided with a suitable means for receiving a hook and extending preferably from the center of the sections.

The outer ends of the flanges 3—3 and 5—5 are each provided with cleats 8, these cleats being secured in any manner to their respective flanges, and having trained there-around the cord 9. There is preferably one cord for each pair of cleats, the particular form shown in the drawings requiring two of these cords 9. It will be seen that when the holder is disposed as shown in Fig. 2, with the upright section 1 held in position,

that the cords 9 may be secured to the upper cleats 8 formed on the section 1 and then led down to the lower cleats formed on the section 2, the angular relation between the 5 two sections being controlled by means of the lengths of the cords 9.

In order that the holder may be supported from a chandelier or other pendant, the holder is provided with a plurality of flexible holders 10, these holders 10 being made of leather, strong cloth or other suitable material, and being secured to each of the holding sections in any manner. Each of these flexible holders 10 is provided with an 15 opening 11 adapted to receive the cord 12, which passes over one of the cleats 8, and extends diagonally across the frame to engage the cleat upon the opposite side of the other section. Each of the holders 10 may 20 be provided with one of these cords 12, and it is preferable to have the crossing cords wrapped around each other for several turns, as indicated at 13, for the purpose of forming a brace or inside guard which may 25 serve to prevent papers, etc., from blowing upon the paper contained within the holder. These cords 12 are adapted to coöperate with the cords 9 in holding the suspended section 2 as shown in Fig. 2, but they also 30 serve the useful purpose of forming with the end cords 9, a suitable guard for the purpose just described.

The fly paper which is designed to be used for this holder, is somewhat longer 35 than the length of the holder when in a flat position, as shown in Fig. 1, the object of having the paper longer being to turn up the ends as indicated in dotted lines in Fig. 2, so that the troughs 4 and 6 will serve not 40 only to hold the ends of the paper in place, but also hold the said ends curved away from the bottom and toward the top of each receptacle as at 14'. The purpose of having these ends curved is to prevent the adhesive 45 material carried by the paper from running off of the paper on to the trough when the holder is in the position shown in Figs. 4 or 5. In order to hold the paper in place, there are provided several clips 14, 50 these clips being pivoted to the bottom of the sections, and adapted to swing over the paper to hold the same in place. As shown in the drawings, there is provided one pair of these clips for each section. If desired, 55 these clips may be omitted, in which case, it will be necessary to depend upon the flanges 3—3 and 5—5, to hold the paper in place.

As shown in Fig. 3, the holder may be 60 hung from a wall, and held in position as shown in full lines, or swung as shown in dotted lines by lengthening the cords 9 and also making corresponding adjustments to the cords 12. In the position shown in dotted lines in Fig. 3, it will be evident that 65 after a short time the adhesive material on

the surface of the fly paper, will fall to the lower trough and collect there, but insomuch as the end of the paper is turned around a center coincident with the excess of the trough, it will be evident that none of 70 the adhesive material will run off of the paper on to the holder. Insomuch as each section is provided with a hanger 7, it will be possible after some of the material accumulates in the lower trough, to reverse 75 the position of the hanger and enable said collected material to run back and thus replenish the surface of the paper.

As shown in Fig. 4, the cords 12 may extend from the holders 10 to the cleats 8, and 80 insomuch as the cords 12 are crossed, and connect to the cleats 8, which cleats are raised somewhat from the plane of the sections, it will be evident that such sections will be held substantially in the position 85 shown, or any other adjusted position, the other adjusted position being obtained by varying the length of the cords 12. There is connecting the holders 10, a flexible cord 15, which may engage a chandelier or other 90 pendant so that the holder may be hung in the center of a room.

As shown in Fig. 5, the upturned sides of the adjacent sections of the holders, are parallel to the wall, the flanges on one side 95 of the holder engaging the wall. The flexible cord 15 in this instance is led over a hook or other suitable supporting means secured in the wall, and the relative angular position of the two sections is obtained by 100 means of the cross cords 12 in a manner substantially the same as described in connection with Fig. 4.

As shown in Fig. 6, the holder may be 105 folded when not in use so as to take up very little room, the hinges and flanges being so related that when the holder folds, the flanges will protect outside objects from the sticky surface of the paper, although the surface of the paper will be exposed. It 110 will also be apparent from Fig. 6, as well as Fig. 1, that if the holder should be overturned, no damage will result thereto, insomuch as the flanges will prevent the paper from coming in contact with other surfaces. 115

The holder may be made of any suitable material, such as light colored wood, or tin, or sheet iron, or other metal. In any instance, it is desirable to have the holder 120 painted some bright color, such as will attract insects and also give a pleasing appearance. Any style of paper may be used within the holder, which will be of sufficient length to allow the ends thereof to be curved upwardly. In practice, it will be 125 possible to use paper which is not of sufficient length to have its ends curved, in which case the troughs 4 and 6 will serve to catch any adhesive material which may run off the paper, but it will be preferable to 130

use the style of paper and have the same disposed in a manner similar to that described herein.

What I claim is:

- 5 1. A device of the class described, comprising a plurality of sections, each including a bottom, side walls, and a receptacle at one end closed except on one side, the opposite end of each section being open, the sections being connected at their open ends and the side walls overlapping adjacent said open ends.
- 10 2. A device of the class described, comprising a plurality of sections, each including a bottom, side walls, and a receptacle at one end closed except on one side, the opposite end of each section being open, the sections being connected at their open ends and the side walls overlapping adjacent said open ends, and a member having a plastic

surface disposed in said sections and having its ends curved away from the bottom and toward the top of each receptacle.

3. In a fly paper holder, a hinged frame, a trough at each end of the frame, cleats 25 carried by the trough, supporting members secured to the frame adjacent the hinging portion of the frame, flexible cords secured to the supporting members, and adjustably engaging the ends of the frame, and means 30 for holding the paper in the frame, said cords supporting the hinged frame and preventing the spreading thereof when in V form.

In testimony whereof I affix my signature 35 in presence of two witnesses.

JOHN J. BUCKLEY.
